US0D1023530S

(12) **United States Design Patent** (10) **Patent No.:** **US D1,023,530 S**
(45) **Date of Patent:** **** Apr. 23, 2024**

(54) **SHOE MIDSOLE**

(71) Applicant: **adidas AG**, Herzogenaurach (DE)

(72) Inventors: **Zachary Coonrod**, Herzogenaurach (DE); **Stuart Reinhartd**, Herzogenaurach (DE)

(73) Assignee: **adidas AG**, Herzogenaurach (DE)

(**) Term: **15 Years**

(21) Appl. No.: **29/882,765**

(22) Filed: **Jan. 18, 2023**

Related U.S. Application Data

(63) Continuation of application No. 29/813,809, filed on Nov. 1, 2021, now Pat. No. Des. 979,193, which is a continuation of application No. 29/774,470, filed on Mar. 17, 2021, now Pat. No. Des. 943,895, which is a continuation of application No. 29/697,489, filed on Jul. 9, 2019, now Pat. No. Des. 916,444, which is a continuation of application No. 29/614,532, filed on Aug. 21, 2017, now Pat. No. Des. 855,297.

(57) **CLAIM**

The ornamental design for a shoe midsole, as shown and described.

DESCRIPTION

FIG. 1 is a lateral side view of an embodiment of a shoe midsole.

FIG. 2 is a medial side view of the shoe midsole of FIG. 1. FIG. 3 is a front lateral perspective view of the shoe midsole of FIG. 1.

FIG. 4 is a front medial perspective view of the shoe midsole of FIG. 1; and,

FIG. 5 is a rear view of the shoe midsole of FIG. 1.

The portions of the shoe midsole surrounded by dashed lines are unclaimed and form no part of the claimed design. The dashed lines are unclaimed boundaries and form no part of the claimed design.

1 Claim, 2 Drawing Sheets
